UNITED STATES PATENT OFFICE.

CHARLES E. BEAN, OF FALL RIVER, MASSACHUSETTS.

DESIGN FOR A KNIT FABRIC.

SPECIFICATION forming part of Design No. 11,976, dated October 12, 1880.

Application filed July 1, 1880. Term of patent 7 years.

To all whom it may concern:

Be it known that I, CHARLES E. BEAN, of Fall River, in the county of Bristol and State of Massachusetts, have invented a new Design for Knit Fabric, of which the following is a specification.

In the accompanying drawing a piece of my newly-designed knit fabric is shown on an enlarged scale.

10 The leading feature of my design consists of a thread enchain'd into loops and of a second looped thread passing through the loops of the first thread.

15 A A is a thread enchain'd into loops B B in the ordinary manner, as in all knit fabrics. D is a second thread forming larger closed loops C and open loops E. A closed loop, C, passes through every third loop, B', of a transverse row of loops, B, and a loop, B², of the 20 next transverse row of loops B passes through

the said loop C, and so on, the closed loops C being connected by open loops E, as shown.

Having thus described my invention, what I claim as new, and desire to secure by Letters Patent, is—

25 The design for a knit fabric herein shown and described, the same consisting of a thread enchain'd into loops and of a second thread formed into large open and closed loops, each one of the larger closed loops passing through 30 one of the smaller loops in a transverse row at regular intervals, whereas the loops of the next transverse row of the smaller loops pass through the larger closed loops at regular intervals, the said large closed loops being connected by large open loops.

CHARLES E. BEAN.
